Primary Examiner — Patricia Palasik

(57) **CLAIM**

The ornamental design for a robot, as shown and described.

DESCRIPTION

FIG. 1 is a front elevational view of a robot showing our new design;

FIG. 2 is a rear elevational view thereof;

FIG. 3 is a left side view thereof;

FIG. 4 is a right side view thereof;

FIG. 5 is a top plan view thereof;

FIG. 6 is a perspective view thereof;

FIG. 7 is a front elevational view of the robot in a first use state;

FIG. 8 is a front elevational view of the robot in a second use state;

FIG. 9 is a perspective view of the robot in a third use state;

FIG. 10 is a perspective view of the robot in a fourth use state; and,

FIG. 11 is a perspective view of the robot in a fifth use state. The broken lines in the drawings depict unclaimed environmental subject matter.

1 Claim, 11 Drawing Sheets
